UNITED STATES PATENT OFFICE.

NORRIS ELMORE CLARK, OF PLAINVILLE, CONNECTICUT.

EXPANDED-METAL MANUFACTURE.

1,224,104.

Specification of Letters Patent. Patented Apr. 24, 1917.

Application filed February 15, 1915. Serial No. 8,354.

To all whom it may concern:

Be it known that I, NORRIS ELMORE CLARK, a citizen of the United States of America, and residing at Plainville, in the county of 5 Hartford and State of Connecticut, have invented new and useful Improvements in Expanded-Metal Manufacture, of which the following is a specification.

My invention relates to a process or 10 method of forming reticulated metal having corrugated or grooved ribs, beams or tension members.

The main object is to provide a simple 15 method of forming such a fabric so that it will have a uniform character of meshwork with relatively small openings and strands so arranged as to afford a maximum reinforcement and bonding effect and at the same time to avoid the setting up of disadvantageous internal stresses.

The preferred form of product is illustrated in my application #480,976 filed March 2nd, 1909, now Patent #1,128,659 dated February 16, 1915, and this application is a partial continuation from said former application.

Briefly considered the process herein claimed contemplates the formation of the product by first slitting sections of a sheet, 30 leaving parallel unslotted portions and then simultaneously bending or folding the unslotted portions into trough-shaped form and thereby bending the strands of the slotted sections to form the meshwork.

The preferred form of slitting is illustrated in my Patent #979,130 but it should be understood that I consider that other arrangements of slitting may be employed for instance, as shown in my Patent 40 #1,086,027. According to the method herein set forth each slotted section is expanded in opposite directions from its center so that the strands lie edgewise relative to their original plane, the strands on opposite sides of the center being inclined in opposite directions.

Figure 1, is an end view showing the stock slotted as shown in my Patent #979,130 and showing diagrammatically mechanism for bending or folding the unslotted portions and thereby opening the meshwork with the strands on opposite sides of the center inclined edgewise in opposite directions.

Fig. 2, is an end view of the finished 55 product.

The stock is first slit by suitable mechanism in the desired arrangement along the sections 5, 5 leaving broad unslotted portions or sections 6, 6. In the form shown the slitting produces relatively narrow bendable 60 strands such as 7, 7. According to the method of slitting illustrated in my Patent #979,130 these strands are cut successively from the stock in the slitting operation so that the strands are inclined somewhat in 65 opposite directions on opposite sides of the center 8 of the slotted section as shown in Fig. 1 hereof.

After the slitting operation, the unslotted portions are bent or folded into channel-like 70 or trough-shaped form by suitable mechanism. In the form of mechanism illustrated herein jaws 10, 10 are hinged or pivoted together at 11 to a number of vertically movable slides 12. These slides and the jaws carried thereby are held pressed upward by a spring 13 and the jaws normally lie open as shown. The cam faces 14, 14 are adapted to swing the jaws toward each other as the jaws are forced downward. A vertically 75 movable punch member or die 15 having the desired shape of the interior of the rib to be formed is mounted over each pair of jaws. There is also preferably mounted midway between adjacent dies 15, 15 an abutment 16 80 adapted to coact with the center of a slotted section. This abutment is preferably vertically movable relative to the dies 15, 15 being pressed downward by a spring 17.

In operation, a slotted sheet is inserted 90 between the upper and lower dies and the upper dies move downward. The dies 15, 15 engage the centers of the unslotted portions and force them toward the corresponding pairs of folding jaws. The edges of the jaws support the edges of the unslotted portions as the centers of the unslotted portions are moved downward. A continued downward movement of the dies 15, 15 forces the jaw carriers downward and thus causes the jaws 95 to be folded toward each other, which folding action folds the edges of the unslotted portions toward the sides of the dies 15, 15, thus stretching or expanding the slotted stock into meshwork between the dies. The folding of the unslotted portions carries their edges upwardly out of their original plane relative to their central portions. The folding 100 of the ribs and the opening of the meshwork bring the edges of the ribs and the 105 110

strands on edge relative to the original plane of the stock, the inclination of the edges of the ribs corresponding to the inclination of the strands attached thereto. The opposite 5 sides of each rib are inclined in opposite directions and similarly the strands between adjacent ribs are inclined in opposite directions on opposite sides of the center. This relative angular relation permits the bending 10 action of the ribs and strands to take place with a minimum application of force and a minimum strain in the fabric. A central abutment 16 facilitates the uniform turning of the strands on edge in opposite directions 15 on opposite sides.

It is preferred that the center of the slotted section 5 be provided with a central unslotted strip or portion as in my application #480,976. When the stock is slotted 20 along diagonal lines it will be necessary to permit this central strip to move longitudinally relative to the unslotted portions 5, 5 during the expanding action. In fact force may be applied by the mechanism to 25 move this central strip longitudinally to facilitate the expanding action.

When there is a central unslotted strip at the center of the slotted section it may be advantageously ribbed or folded into channel-like form by the coaction of a die 18 and the abutment 16. This draws the sides of the central unslotted strip so that they are substantially parallel with the edge-wise inclination of the strands attached 35 thereto. In this way the strands are allowed to bend in a natural manner without being strained. The centers of the expanded sections may be carried into the plane of the edges of the deep ribs by movement of the members 18 and abutments 16 40 relative to the dies 15 and jaws 10.

With the slitting as shown in my Patent #1,086,027 it is unnecessary for the center of the slotted section to move longitudinally. 45 Such a fabric can be expanded by folding the unslotted portions progressively in a series of bending rolls.

The product shown in Fig. 2 may be still further expanded by laterally movable jaws 50 or by passing it through diverging rolls or guides so as to obtain a product of greater width than the original stock if desired.

What I claim is:—

1. The improvement in the art of making expanded metal which includes first slitting portions of a sheet in staggered arrangement to form inclined bendable strands and leaving broad unslotted portions, said strands being inclined in opposite directions on opposite sides of the center between the unslotted portions, then forming relatively deep parallel trough-shaped ribs by engaging the centers and outer edges of the unslotted portions 60 and folding the sides of said portions out

of their original plane, thereby turning the strands at one side of the center of the intervening slotted section in opposite angular relation to the strands of the other side of said slotted section simultaneously with the opening of the meshwork. 70

2. The improvement in the art of making expanded metal which includes slitting sections of a sheet in staggered arrangement to form bendable strands and leaving broad unslotted portions, folding the edges of the unslotted portions out of the plane of the centers of the slotted sections, thereby opening meshwork with the strands of halves thereof arranged in opposed angularity between the folded members. 80

3. The improvement in the art of making expanded metal which includes slitting sections of a sheet in staggered arrangement and leaving unslotted portions, holding portions of the slotted sections on opposite sides of an unslotted portion and folding the edges of the unslotted portion to form a grooved beam member and thereby carrying the attached edges of the slotted sections out of their original plane to form meshwork. 90

4. The improvement in the art of forming expanded metal which includes forming a plurality of rows of relatively short slits leaving strands connected in staggered arrangement in a section of a sheet and leaving relatively broad unslotted portions at opposite edges of the slotted section folding the broad unslotted portions to form beams and moving their edges out of their original plane in advance of the center of the slotted section and then moving the center of the slotted section into the plane of the edges of the beams. 100

5. The improvement in the art of making expanded metal which includes first slitting sections of a sheet in staggered arrangement so as to produce bendable strands and leaving broad marginal and intermediate narrow unslotted portions, then folding said unslotted portions into alternate deep and shallow channels facing in opposite directions and moving adjacent edges of adjacent unslotted portions into different planes thereby producing open meshwork and then bringing the edges of all of said channels into a common plane. 110

6. The improvement in the art of making expanded metal which includes first slitting a section of a sheet to form narrow inclined bendable strands connected together in staggered relation between broad unslotted portions, the strands being inclined in opposite directions on opposite sides of the center of the slotted section and then simultaneously bending the unslotted portions into channel-like form and thereby bending the strands and stretching the meshwork so that the strands at the oppo- 120 125 130

site sides of the center of the meshwork are arranged inclined edgewise in opposite directions in a common plane.

7. The method of forming a ribbed expanded metal product from a sheet having longitudinal unslotted strips and an intervening slotted expansible section which comprises folding the longitudinal unslotted strips to form grooved beams or ribs and at 10 the same time holding the central part of the intervening slotted section relative to the edges of said unslotted strips and thereby opening the opposite halves of the slotted section in opposite directions away from 15 the center thereof.

8. The method of forming a ribbed expanded metal product which comprises first slitting a section between longitudinal unslotted strips so as to form strands inclined 20 in opposite directions away from the center of said section and then folding the unslotted strips and thereby stretching the slotted section in opposite directions away from the center of said section to form 25 meshwork with strands inclined edgewise in opposite directions in the two halves thereof.

9. The method of forming a ribbed expanded metal product from a sheet having longitudinal unslotted strips and an intervening slotted expansible section which comprises folding the longitudinal unslotted strips and moving the edges thereof from the plane of the central part of the intervening slotted section to form grooved 35 beams or ribs and at the same time holding the central part of the intervening slotted section relative to the edges of said unslotted strips and opening the opposite halves of the slotted section in opposite directions 40 away from the center thereof, and then bringing the central part of the slotted section and the edges of the unslotted strips into a common plane.

10. The method of forming a ribbed expanded metal product which comprises first slitting a section between longitudinal unslotted strips so as to form strands inclined in opposite directions away from the center of said section and then folding the un-

slotted strips and moving the edges thereof out of the plane of the center of said slotted section thereby stretching the slotted section in opposite directions away from the center of said section to form meshwork with strands inclined edgewise in opposite directions in the two halves thereof and bringing the central part of the slotted section and the edges of the unslotted strips into a common plane.

11. The method of forming a ribbed expanded metal product which comprises slitting a section of a sheet in staggered arrangement, leaving unslotted strips at each side thereof, moving the center of the slotted section out of the plane of the adjacent edges of the unslotted strips in one direction, then moving said edges in the opposite direction away from the center to open the slotted section.

12. The method of forming a ribbed expanded metal product which comprises slitting a section of a sheet in staggered arrangement, leaving unslotted strips at each side thereof, moving the center of the slotted section out of the plane of the adjacent edges of the unslotted strips in one direction, then moving said edges in the opposite direction away from the center to open the slotted section and then moving said edges into the plane of the center.

13. The method of making expanded metal, which comprises slitting sections of a sheet with a plurality of relatively short slits to form strands connected by bonds in staggered arrangement and leaving marginal and interior unslotted strips, then moving alternate unslotted strips in one direction out of the original plane of the stock, and moving the adjacent edges of the remaining strips in the opposite direction out of the original plane to open the slotted sections and form meshwork and then moving all the slotted sections into a common plane.
